UNITED STATES PATENT OFFICE

WILLIAM M. GOLDSMITH, OF CINCINNATI, OHIO, ASSIGNOR TO THE GOLDSMITH METAL LATH COMPANY, OF CINCINNATI, OHIO, A CORPORATION OF OHIO

SPREADER FOR USE WITH METAL TILES

Application filed March 24, 1927. Serial No. 177,922.

This invention relates to a device for positioning and supporting forms or tiles used in concrete floor construction.

An object of the invention is to provide means whereby a form or tile may be retained against displacement and adjustably positioned relative to a temporary supporting structure for forming a beam of any desired depth.

10 Another object is to provide a device which will suspend a form or tile upon the temporary structure and at the same time preclude collapsing of the tile due to force exerted thereon by plastic concrete.

15 Another object is to provide a device for the purposes stated which may be readily removed after the concrete forming the floor and beams has set, for permitting removal of the forms or tiles.

20 Another object is to provide a device for the purposes stated which may be cheaply manufactured, and assembled in a manner such that loss of its various parts is impossible.

25 These and other objects are attained by the means described herein and disclosed in the accompanying drawings, in which:

Fig. 1 is a cross sectional view showing the device of the present invention supporting a 30 form or tile about which concrete has been poured for forming a floor and beams.

Fig. 2 is a view taken on line 2—2 of Fig. 1.

Fig. 3 is a side elevational view of the device showing the parts in an inoperative position.

35 Fig. 4 is a sectional view on line 4—4 of Fig. 3.

The device comprises a housing 8 built up of a pair of identical side plates 9 and 10 which are preferably sheet metal stampings 40 each having a flange 11 and a grooved portion 12. The side plates are secured one upon another by any suitable securing means such as spot welding 13 whereby the grooves 12 in each side plate cooperate for forming a bearing 45 for a pair of longitudinally slidable support members or bars 14 each having a handle portion 15 and a free end 16. The handle portions 15 extend downwardly from the housing through an enlarged opening or way 50 17 in which the handles may be reciprocated

longitudinally of the housing for disposing the free end 16 of the support member either within the housing as shown in Fig. 3, or extended from the housing as shown in Figs. 1 and 2 for supporting the form or tile 18 55 upon aligned rows of soffits 19 supported in a well known manner upon shoring 20.

Each of the side plates 9 and 10 is provided with a slot 21 extending from the lower edge 22 thereof to a point slightly beyond the bearing or groove 12 for permitting oscillation of the rods 14 in the bearing 12 whereby the handles 15 may assume the operative position shown in Figs. 1 and 2. It is obvious that in the above referred to operative position, the free ends 16 of rod or support member 14 are extended beyond the housing and may not be moved from the extended position except by subsequent oscillation of the handles into the plane of the side members, 60 65 whereupon the handles are disposed in alignment with way 17 and may then be moved longitudinally within the way for drawing the free ends 16 into the housing 8.

To preclude accidental movement of the 75 handles 15 from the operative position shown in Figs. 1 and 2, a locking device is provided comprising a lever 23 pivotally mounted upon the housing at 24 and adapted for movement to the position shown in Fig. 2 for 80 locking both handles 15 in the operative position. A nail 25 or other object may then be passed through coinciding perforations 26 and 27 in the lever and housing respectively for precluding movement of the locking device. To permit ready manipulation of the 85 lever 23, a suitable extension 28 may be provided on the end thereof as shown.

The operation of the device is as follows: After the temporary structure comprising 90 soffits 19 has been erected, the forms or tiles 18 for forming beams 29 and floor 30 are brought into position adjacent the soffits 19. The device of this invention with the free ends 16 disposed within housing 8 as shown 95 in Fig. 3 is then inserted between the side walls 31 of the tiles and handles 15 are actuated to extend the rods or support members 14 as shown in Figs. 1 and 2. The ends 16 of said rods are received by perforations 32 100

in the side walls 31 of the form and extend therethrough for a distance sufficient to permit ends 16 to rest upon the top surface of soffit 19 for suspending the form. The handles 15 are then oscillated to the position shown in Figs. 1 and 2 and locked by locking device 23. It should be noted that by providing tile 18 with a plurality of perforations 32 for receiving ends 16 of the device of this invention the tile may be raised or lowered relative to the soffits whereby beams 29 of various proportions may be formed.

After positioning aligned rows of tiles in the above manner, plastic concrete is poured about the tiles and allowed to set for forming the beams and floor. It should be noted that concrete forming the beam 29 when in a plastic state tends to collapse tile 18 by bending the side walls thereof inwardly. The device of this invention being of a length substantially equal to the distance between the side walls of the tile, precludes collapsing of said walls.

After the concrete has set, tiles or forms 18 are to be removed. The locking device is first actuated to permit oscillation and movement of handles 15 to the position shown in Fig. 3. It should be noted that movement of the handle 15 in the slot 21 loosens the end 16 from the concrete of the beam 29 in which the end 16 becomes embedded while the concrete is setting. After said ends are thus freed, the support rods 14 may be reciprocated to the inoperative position shown in Fig. 3 whereupon the entire device may be withdrawn from the inside of the form and the form severed from the concrete.

It should be noted that the construction of the housing 8 as shown in Fig. 4 is such that the device will withstand considerable compression strain exerted thereon by the side walls 31 when the concrete forming the beam is poured. Another important feature is the few parts needed for the manufacture of the device. The parts required are two identical side plates, two identical support bars 14 and a lever 23 having a pivot 24. Exclusive of the pivot 24, it is necessary to manufacture only the three independent parts above mentioned. The device is assembled so that there are no loose parts to become detached and lost.

What is claimed is:

1. The combination with a form having opposed perforate side walls, of a support and spreader means therefor comprising an elongated hollow housing adapted for insertion between the side walls for precluding inward collapsing of said walls, a pair of longitudinally reciprocable and oscillatory support members each having a free end and a handle for reciprocating and oscillating the support member relative to the housing whereby the free ends may enter the perforations in the side walls of the form and extend beyond the

side walls for positioning the housing and supporting the form.

2. In a spreader and supporter for forms, the combination of a hollow housing comprising a pair of identical housing members, a pair of identical reciprocable and oscillatory support members inclosed within the housing, each having a free end and a handle portion for imparting to said free ends longitudinally reciprocating motion relative to the housing for extending the free ends beyond the ends of the housing and for oscillating said support member in its extended position.

3. In a device of the class described, the combination of an elongated hollow housing, a pair of relatively reciprocable and oscillatory movable support members inclosed within the housing each having a free end and a handle portion for imparting to said members oscillatory and reciprocating motion relative to the housing for extending the free ends beyond the length of the housing, and means for locking the support members in the extended position.

4. In a device of the class described the combination of an elongated housing adapted for insertion between the perforate side walls of a form for precluding inward collapsing of the form, a pair of longitudinally reciprocable and oscillatory support members carried by the housing each having a free end adapted in extended position to be received in the perforations in the said side walls and to extend beyond the side walls whereby the form may be suspended from said free ends of the support members.

5. In a device of the class described, the combination of an elongated housing adapted for insertion between the perforate side walls of a form for precluding collapsing of the form, a pair of longitudinally reciprocable support members carried by the housing and each having a free end adapted to be extended beyond the housing and through the perforations in the side walls whereby the form may be suspended, means for locking the said support members in extended position, and means for retaining the locking means in an operative position.

6. In a device of the class described, the combination of an elongated housing adapted for insertion between the perforate side walls of a form for precluding collapsing of the form, a pair of longitudinally movable extensible members carried by the housing and adapted to be longitudinally extended beyond the housing and received in the perforations in the side walls of the form for positioning the housing relative to the form, the housing having ways within which the extensible members may be lodged for retaining them in extended position and movable means precluding inadvertent dislodgement of the extensible members from the ways.

7. A spreader comprising a housing mem-

ber having a way extending lengthwise therethrough, the housing having a second way intercepting the first mentioned way, the opposed sides of the housing having openings in them, said openings being disposed at opposite ends of said second way, and a pair of round rods in said first mentioned way, said rods having each an angular extension formed thereon, said extensions lying in and projecting from said second way, said extensions being adapted for entry in the openings at the ends of said second way, and serving as handles for oscillating the rods in the first mentioned way and for reciprocating said rods in said first mentioned way whereby to project said rods outwardly from opposite ends of said housing and for withdrawing the rods into the housing, the handles, when lodged in the said openings, precluding reciprocation of the rods.

8. A spreader comprising a housing member having a way extending lengthwise therethrough, the housing having a second way intercepting the first mentioned way, the opposed sides of the housing having openings in them, said openings being disposed at opposite ends of said second way, and a pair of round rods in said first mentioned way, said rods having each an angular extension formed thereon, said extensions lying in and projecting from said second way, said extensions being adapted for entry in the openings at the ends of said second way, and serving as handles for oscillating the rods in the first mentioned way and for reciprocating said rods in said first mentioned way whereby to project said rods outwardly from opposite ends of said housing and for withdrawing the rods into the housing, the handles, when lodged in the said openings, precluding reciprocation of the rods and means for locking the handles in said openings.

9. A spreader comprising a housing having a longitudinal way and openings communicating with said way, a pair of extensible members in the way, means on the extensible members for entry into the openings for retaining the extensible members in projected positions and a movable lock member for retaining said means in said openings.

10. A spreader comprising a housing having a longitudinal way and openings communicating with said way, a pair of extensible members in the way, means on the extensible members for entry into the openings for retaining the extensible members in projected positions, a pivotally mounted means for closing the openings to preclude inadvertent dislodgment of the extensible members and an insertable means for retaining the pivotally mounted means in the last mentioned position.

In testimony whereof, I have hereunto subscribed my name this 19th day of March, 1927.

65 WILLIAM M. GOLDSMITH.
